UNITED STATES PATENT OFFICE.

IRVING BARKER, OF SPRINGFIELD, ILLINOIS.

APPARATUS FOR CASTING METALS.

SPECIFICATION forming part of Letters Patent No. 784,023, dated March 7, 1905.

Application filed May 9, 1904. Serial No. 207,047.

To all whom it may concern:

Be it known that I, IRVING BARKER, a citizen of the United States, residing at Springfield, in the county of Sangamon and State of Illinois, have invented a certain new and useful Apparatus for Casting Metals, of which the following is such a full, clear, and exact description as will enable others skilled in the art to which it appertains to make and use my said invention.

My invention relates to an apparatus for casting metal articles—such as car-wheels, axle-boxes, &c.—and adapted for forming during the operation of casting straight and smoothly-finished holes through wheel-boxes, the hubs of wheels, guide-blocks, or other similar cast metal articles, and also for producing during the operation of casting flattened smoothly-finished surfaces on the cast article suitable for the contacting surfaces of wearing parts or suitable for the fitting of other parts on said cast article without the necessity for planing or otherwise preparing the surface of the cast article.

I will hereinafter describe the apparatus as employed in the manufacture of mine-car wheels; but obviously it may be advantageously used in making other and different articles—such as axle-boxes, pillow-blocks, guide-blocks, &c.—without departing from my invention.

The purposes of my invention are to provide an apparatus whereby the inner surface of the hub of a wheel or other cast article, poured in a melted condition around a mandrel of iron or other suitable material adapted to chill the interior of the hub or the interior of the part contacting with the mandrel, may be cooled by cold water or other cooling medium applied within the mandrel, causing the latter to contract, so that it may be easily withdrawn from the cast article; to provide an apparatus adapted to produce a smooth finish of one or more faces of the article, suitable for wearing-surfaces or suitable for connecting other parts with said articles, without the necessity for boring, planing, or otherwise finishing said article, and to provide an apparatus which when employed in the casting of car-wheels

or the like is adapted to produce from a single wheel-pattern used with a single mandrel wheels fitting on axles of different lengths, measured from outside to outside of the collars on the axles, without changing the wheel-gage, measured from the outside of the flanges of the wheels.

With these ends in view my invention consists in an apparatus embodying the means and appliance, hereinafter described, and particularly recited in the claims.

In order that my invention may be clearly understood, it is necessary to briefly describe the state of the art prior to my invention.

I am aware that tapering solid cast-iron mandrels have long been used for the purpose of chilling molten metal poured around a tapering mandrel, so as to harden the inner surface of the metal coming in contact with the mandrel; but such mandrels have always heretofore been made tapering in order that they may be driven out of the hub of the article.

The use of a tapering mandrel necessarily produces a tapering hole through the article, and in the case of a rotating article, such as a wheel, necessitates the tapering and finishing of the axle or spindle on which the wheel or other part runs to conform to the taper of the mandrel.

The turning and tapering of axles or spindles involves labor and expense. Furthermore, it is found in practice that tapering axles or spindles are objectionable on account of the tendency of the rotating part to run off the axle or spindle, thereby producing undue wear and friction against the lynch-pin or other device retaining the rotating part on the axles or spindles.

Prior to my invention it has been found impracticable to produce a cast wheel-hub having a straight and smooth inner surface or a cast guide-block or axle-box or other similar article having a straight and smooth inner surface, because the shrinkage of the metal around a straight solid mandrel binds and holds the casting on the mandrel so tightly that the mandrel cannot be driven out of the casting without battering the mandrel to such extent as to render it unfit for future use.

In the manufacture of car-wheels having an oil-chamber and wheel-caps, also having in one end of the hub a counterbore in which the collar on the axle fits and at the other end of 5 the hub a smooth flat surface running in contact with a lynchpin, the practice has heretofore been to cast the wheel with flat but not smooth surfaces at the ends of the hub and on one face of the wheel and then plane or otherwise 10 finish the flat surfaces so that the cap may be accurately fitted thereon to prevent leakage of oil from the oil-chamber and so as to present smooth surfaces at the ends of the hub in contact with the collar and the lynchpin. 15 This procedure involves unnecessary labor and expense.

A prime purpose of my invention is to provide an apparatus adapted to overcome all of these difficulties and produce at a minimum 20 cost a wheel or other article having a straight central hole through its hub or body, such that the wheel or other article will turn on a straight axle or spindle, or such that a straight shaft, either round or polygonal, as the case 25 may be, may fit closely and slide freely in the smooth-finished hole through the cast article, and also to provide means adapted to produce a wheel or other article having smooth contact-surfaces completely finished during the 30 operation of casting the article.

In casting a car-wheel having an oil-chamber and a cap I preferably employ the appliances shown in the drawings hereto annexed and to which reference is hereby made; but 35 others slightly-modified forms of the appliances obviously may be employed by those skilled in the art in making wheels or boxes or other articles having straight bores or holes finished smoothly during the operation of casting without departing from my invention, it being essential 40 only to employ a mandrel so constructed and arranged that a cooling medium may be applied within the mandrel to cause the cooling and shrinkage of the mandrel and the consequent chilling of the inner surface of the 45 hub of the wheel or other article.

I illustrate in the drawings and will herein-after describe a preferable form of the apparatus employed in the manufacture of a mine-car wheel provided with an oil-reservoir and a cap and having hubs smoothly finished at the ends.

Referring to the drawings, Figure 1 is a vertical axial section through a sand mold, 55 showing a car-wheel and the center plate in position in the mold and the mandrel in position in the hub of the wheel. Fig. 2 is a detached side elevation of the mandrel and the means for supplying a cooling medium within 60 the mandrel. Fig. 3 is a top plan of the center plate supporting the mandrel, and Fig. 4 is a horizontal section on the line 4-4 of Fig. 1.

Similar reference-letters designate like parts in the several views.

65 The main structure of the wheel A may be

of any usual and well-known form and need not be particularly described.

The mandrel B is a straight and smoothly-finished cylinder, preferably of cast-iron, and has a central bore b, within which a cooling 70 medium may be caused to circulate by means of a nozzle or equivalent device inserted in the central bore of the mandrel, as shown in Fig. 2 and as hereinafter explained. At one end of the mandrel is a tapering hub b', which 75 fits in a central tapering hole C' in the plate C and supports the mandrel in the mold in a vertical position relative to the plate. At the other end of the mandrel is an integral collar b'', which projects beyond the periphery of 80 the mandrel and serves to form the counterbore a in one end of the hub of the wheel and has a flat and smooth surface adapted to give a smooth finish to the bottom of the counterbore in the hub of the wheel. 85

The center plate C has a flat and smooth surface which serves to flatten and smooth one face of the wheel and one end of the hub of the wheel. It also has a central hole C', in which the tapering hub of the mandrel fits. 90 It also has equidistant recesses C'', adapted to receive lugs on the cores employed in forming the central oil-chamber in the body of the hub.

The hole C' and the recesses C'' of the plate 95 C are so situated as to assure absolute accuracy in the setting of the mandrel B and the core a'.

Preliminary to casting a wheel the pattern of the body of the wheel A is placed in the 100 drag of the flask with the plate C centrally situated above the hub of the wheel-pattern. Sand is then tamped around the wheel-pattern and around the plate C in the usual manner, and the pattern is then withdrawn and 105 the mandrel inserted. The cope is then prepared and secured on the flask, and the melted metal, is poured in the usual manner. The wall of the hollow mandrel being thin and its outer surface being smooth and its mass much 110 less than the mass of the surrounding molten metal the heat of the metal quickly expands the mandrel before the melted metal sets, so that the mandrel produces a smoothly-finished hole in the metal slightly larger than the mandrel, 115 and when the mandrel is quickly cooled while the metal is still hot the mandrel shrinks and may be easily removed without injuring the mandrel. When the metal has set in the mold, 120 the wheel is removed from the flask while still hot. A pipe or hose D is then inserted in the open end of the mandrel, and cold water or other cooling medium is caused to flow into the central chamber in the mandrel, thereby cooling 125 the mandrel and causing it to shrink so that the mandrel may be easily withdrawn from the hub. After the withdrawal of the mandrel the cooling medium may be applied to the thick parts of the hub and the adjacent thick parts 130 of the spokes, so as to cool the central parts

of the hub and spokes sufficiently to prevent breakage of the spokes by the too rapid cooling of the rim of the wheel. The wheels are then placed in an annealing-pit, where they cool gradually.

From the foregoing description it will be seen that by cooling and contracting the mandrel as described it is caused to shrink so that it may be readily withdrawn from the wheel, and the smooth surface of the mandrel gives a smooth finish to the bore of the wheel, and the same mandrel may be used an indefinite number of times.

By employing the center plate as described a flat surface is obtained on one face of the central part of the wheel, against which the cap fits closely, so as to prevent leakage of oil from the oil-chamber.

It is found in practice with respect to wheels and axles designed to run on tracks of the same gage and having the same diameter of bore, also having spindles of the same diameter, that there are often material differences in the length of the bore of the hub of the wheel, such that a set of wheels designed to run on one axle will not fit the track-gage if placed on another axle. Car-wheels are subject to hard usage, and it is frequently necessary to replace broken wheels differing as described. In making such odd wheels prior to my invention it has been necessary in each case to change the wheel-pattern in order to produce the necessary change in the length of the bore of the hub of the wheel. This procedure involves labor and expense. I avoid this difficulty and produce, by means of a single wheel-pattern used with a single mandrel, odd wheels having bores of different lengths and adapted to run on axles of different lengths, measured from outside to outside of the collars on the axles, without changing the wheel-gage measured between the outsides of the wheel-flanges. I accomplish this result by making a central counterbore C³ in the center plate C. The counterbore C³ is of a size suitable to accommodate that part of the hub of the wheel to be cast around the part of the mandrel next to the hub b'. By increasing or diminishing the depth of the counterbore the depth to which the mandrel enters the plate C may be changed to suit the circumstances of each particular case. For example, if it is desired to cast a wheel having a bore somewhat longer than the bore of the wheel shown in the drawings it will only be necessary to increase the depth of the counter-bore C³ to the desired extent, as indicated by dotted lines in Fig. 1, and then use a correspondingly-longer mandrel. On the other hand, if it is desired to decrease the length of the bore of the wheel it will only be necessary to diminish the depth of the counterbore by inserting washers C⁴ or equivalent devices having smoothly-finished flat surfaces adapted to give a smooth finish to the end of the hub of the wheel. In practice the

variation in the lengths of the hub-bores is not large. Ordinarily it does not exceed one-quarter of an inch in a wheel.

By making the plates C of suitable thickness the depth of the counterbore C³ may be varied to meet the conditions without any material change in the body of the plate; but if deemed desirable different plates C, having different counterbores C³, may be used with the same mandrel, or mandrels of different lengths may be used with the same center plate without departing from my invention.

When the washers C⁴ are employed, the mandrel enters the sand of the cope to a degree corresponding to the number of washers used.

Having fully described my invention, what I claim as new, and desire to secure by Letters Patent, is—

1. A mandrel for casting metals, consisting of a straight hollow body part smoothly finished externally and having a central bore closed at one end and extending practically the full length of said mandrel and a straight integral collar smoothly finished externally; in combination with a matrix and means for supporting said mandrel centrally in said matrix; said matrix and mandrel being so constructed and arranged as to produce at one casting an article having a straight smoothly-finished bore and a straight smoothly-finished counterbore, as set forth.

2. In an apparatus for casting metals, the combination of a matrix, a center plate supported in said matrix and having a flat smooth surface, and a central hole, a straight hollow mandrel smoothly finished externally having a part fitting in the central hole of said center plate also having a straight integral collar, the bore of said mandrel extending the full length of the article to be cast; said matrix, center plate and mandrel being constructed and arranged to produce at one casting an article having a smooth flat face, a smooth straight bore and a smooth straight counterbore, as set forth.

3. In an apparatus of the class described, the combination of a matrix, a center plate supported in said matrix and having recesses to receive the lugs of a core, a core having lugs fitting in the recesses in said center plate, and a hollow mandrel smoothly finished externally, and central and vertical to said center plate, as set forth.

4. In an apparatus of the class described, the combination of a matrix, a centrally-perforated center plate supported in said matrix, and having a smoothly-finished surface coincident with a surface of said matrix also having recesses adapted to receive the lugs of a core, a core having lugs fitting in the recesses in said center plate, and a hollow mandrel fitting in the central hole of said center plate, as set forth.

5. In an apparatus of the class described,

- the combination of a matrix, a center plate supported in said matrix and having a central recess, means for varying the depth of the recess in said center plate, and a mandrel central to said center plate, as set forth.
6. In an apparatus of the class described, the combination of a matrix, a center plate supported in said matrix, and having a central recess of variable depth, said center plate
- 10 also having recesses adapted to receive the lugs of a core, a core having lugs fitting in the last-named recesses in said center plate, means for varying the depth of the central recess of the center plate, and a hollow mandrel central to said center plate, as set forth.
- 15

7. In an apparatus of the class described, the combination of a matrix, a center plate in said matrix and having a central bore a counterbore, perforated plates fitting in the counterbore of said center plate, and a hollow mandrel having a reduced part fitting in the holes in the plates in the counterbore of the center plate, as set forth. 20

In witness whereof I have hereunto signed my name, at Springfield, Illinois, this 5th day 25 of May, 1904.

IRVING BARKER.
